INTERMITTENT LIFT OF LIQUIDS

Mehmet R. Tek, Bartlesville, Okla., assignor to Phillips Petroleum Company, a corporation of Delaware

Application August 2, 1954, Serial No. 447,323

8 Claims. (Cl. 103—165)

This invention relates to a method and apparatus for lifting liquids. In one of its aspects, this invention relates to a method and apparatus for lifting oil from a low pressure producing formation. In still another aspect, this invention relates to a method and apparatus for intermittent lift of liquids by a column of liquid and pressurized gas.

In pumping or lifting liquids to great heights, many types of lifting apparatus are well known in the art. Where there is a constant supply of liquid and where the pumping apparatus can be conveniently installed at a level below the liquid level, no particular problem is involved. However, where the liquid supply is intermittent, or it is not desirable or practical to mount the lifting apparatus below the liquid level such as would be encountered in a low pressure oil well, particularly near the ends of its producing life, special equipment is needed. For example, in the production of oil, suction rod pumps, hydraulic pumps located in the bottom of the well, electric positive displacement pumps similarly located, gas lift and many other methods have been used. With the electric positive displacement pumps, the installation and maintenance cost are high and this equipment is primarily used for high rates of production. When using a hydraulic pump installed in the bottom of the well, it is necessary to use an extremely clean and high pressure oil for power and it is also necessary to have the pumps mechanically installed in the bottom of the well; however, this type of installation is relatively expensive and is primarily used for medium or high rates of production. When the rate of production becomes low, sucker rod pumps can be used, but these pumps require considerable power and maintenance. Gas lifts have been used for producing oil wells at low rates, however, there is considerable slippage and slight back pressure is placed on the formation when this method is used.

An object of this invention is to provide a method and apparatus for lifting liquids.

Another object of this invention is to provide a method and apparatus for lifting oil from a low pressure producing formation.

Still other objects and advantages of this invention will be obvious to those skilled in the art upon reading this disclosure and the attached claims.

This invention can be used to lift a liquid to great heights and has particular value in producing oil from low pressure wells. For that reason, I shall describe my invention in terms of producing oil.

In the practice of this invention a U-tube is installed in a well with the U at a position near the producing formation. The bottom of the U-tube is connected through a three-way valve with a straight tube which in turn extends down into the producing formation. At the start of each lifting cycle, the three-way valve is turned so that oil can flow from the producing formation through the straight tube into one leg of the U-tube. The other leg of the U-tube will be filled with a lift liquid which can be the same as the liquid being lifted or a liquid

heavier than and non-miscible with the oil such as water. When the oil has risen part way in one leg of the U-tube, the three-way valve is turned so as to connect the two legs of the U-tube. The liquid in the second leg of the U-tube then begins to flow from that leg to the other leg lifting the oil ahead of it. At the same time the U-tube is turned to connect the two legs, sufficient additional pressure is applied to the flowing, non-miscible liquid so as to overcome friction and to lift the column of oil. When all of the non-miscible liquid has flowed to the other leg, the three-way valve is turned to hold this liquid in the other leg and to open the straight tube to the leg of the U-tube previously containing the non-miscible liquid. At the same time, pressure is released from the now liquid-free leg and the cycle repeated.

If one leg of the U-tube should be filled with water and the other leg has a small amount of oil therein, then, when the valve at the bottom of the tube is opened, the water begins to flow from the first tube to the second tube pushing the oil in the second leg ahead of it. At the same time a boosting force is applied to the liquid in the first leg so as to completely move the liquid from said first leg to the second leg. Since the oil rides on top of the water it is pushed over the top level of the U-tube when that leg of the U-tube is filled with the water.

My invention will be further explained by referring to the attached drawings of which:

Figure 1 is an elevation view, partially in section, of an embodiment of my invention where the extra force supplied is by means of gas pressure,

Figure 2 is an elevation view, partially in section, of an embodiment of my invention where the extra force supplied is by means of a pump,

Figure 3 is a cross sectional view of a control system when the three-way valve of the U-tube is in the initial position,

Figure 4 is a cross sectional view of the control system when the three-way valve of the U-tube is in the second position,

Figure 5 is a cross sectional view of the control system when the three-way valve of the U-tube is in the third position, and

Figure 6 is a cross sectional view of the control system when the three-way valve of the U-tube is in the fourth position.

Since my invention is particularly adapted to producing oil from a low pressure well and since water is relatively inexpensive and is generally in plentiful supply, I shall discuss the drawings in terms of producing oil using water as the lifting liquid. In that embodiment of my invention wherein compressed gas is used for the additional force, I shall use compressed air as a readily available and inexpensive gas.

Referring to Figure 1, a U-tube comprised of legs 1 and 2 is positioned in well 3 with the bottom of the U-tube being located near the producing formation 4. Located in the bottom of the U-tube is a three-way valve 5 which is in turn connected to tube 6 which projects down into the producing formation. The well is sealed above the producing formation by packer 7. Each of the two legs 1 and 2 is connected to storage conduit 8, leg 1 through valve 9 and leg 2 through valve 10. Compressed gas conduit 11 is connected through valve 12 to leg 1 intermediate the maximum lift liquid level and valve 9 and to leg 2 intermediate the maximum lift liquid and valve 10 via valve 13. Each of these valves 5, 9, 10, 12 and 13 is connected to power operating means which are in turn operably connected to controller 14. A liquid sensing element 15 is operably installed in leg 1 closely spaced to the three-way valve 5 and liquid sensing element 16 is operably installed in leg 2 and closely spaced to the opposite side of valve 5. Also liquid sensing element 17

is installed in leg 1 at a position below the head pressure of the producing formation and liquid sensing element 18 is similarly installed in leg 2. That is, if the well has sufficient pressure to force the oil part way up the U-tube leg, then the sensing elements 17 and 18 would not have to be located below the actual liquid level. All of these sensing elements are operably connected to the controller 14. Check valve 24 is installed in tube 6 to prevent oil run back and accidentally putting a back pressure on the formation. The operation of my lift will now be explained.

At the beginning of the cycle, valve 5 will be turned so as to connect leg 1 with the tube 6 as is shown in Figure 3. Leg 2 will be full of water. Valve 9 will be open and valve 10 closed. Valve 12 will be closed and valve 13 open thus providing for pressure on the water in leg 2. Oil from the producing formation 4 rises through tube 6 and leg 1 until it reaches the liquid sensing element 17 which sends a signal to controller 14 as explained below. The controller in turn activates a power means for turning valve 5 so as to connect the two legs of the U-tube as is shown in Figure 4. A suitable means for sensing liquid level and controlling these valves is described below. When the valve reaches this position, the water column in leg 2 flows to leg 1 there being sufficient pressure from conduit 11 to lift the oil in leg 1 and to overcome the friction of flow. When the water level from column 2 passes element 16 and no further signal is received by controller 14, power means are activated to turn valve 5 so as to connect tube 6 with leg 2 as is shown in Figure 5 and to simultaneously close valves 9 and 13 and to open valves 10 and 12. The cycle is now repeated in the opposite direction, that is the oil rises in leg 2 until it contacts element 18 and water flow from leg 1 to leg 2 until the level reaches element 15.

From the foregoing description of the operation of my invention, it will be obvious that many modifications can be made in the apparatus without departing from the scope of the invention. For example, valves 9 and 12 can be replaced by a single three-way valve as can valves 10 and 13. These valves would then work in the same manner as do valves 20 and 21 as will be described in connection with Figure 2.

No particular control apparatus or liquid sensing element is required it being within the skill of the art to supply these. However, one suitable system is shown in Figures 3, 4, 5 and 6. Referring to Figure 3, leg 2 of the U-tube is full of the lift liquid (water), and valve 5 is turned so as to open to leg 1 and tube 6. The liquid to be lifted (oil) rises in leg 1 first contacting liquid sensing element 15 which comprises a float and an associated mercury switch 15a. When the float rises, the switch 15a is tripped and the electrical contact is broken. This removes the current from solenoid 25 and allows ratchet 26 to slide back engaging ratchet wheel 27 as is shown in Figure 4. The oil continues to rise in leg 1 until it contacts sensing element 17. The float of this element rises and trips mercury switch 17a and completes the electrical circuit which in turn activates solenoid 29 pulling ratchet 30 and turning ratchet wheel 31 by 90 degrees. This ratchet wheel 31 is connected through mechanical linkage 28 to valve 5 and switch 32. When solenoid 29 is activated, valve 5 is turned 90 degrees so as to connect the two legs as is shown in Figure 4 and switch 32 is turned 90 degrees breaking the electrical circuit across said switch. With valve 5 in the position as shown in Figure 4 the water flows from leg 2 to leg 1 pushing the oil ahead of it. When the water level in leg 1 falls below element 18, the associated mercury switch 18a is opened and solenoid 33 is deactivated allowing ratchet 34 to engage ratchet wheel 35. As the level continues to fall in leg 2, element 16 is contacted and mercury switch 16a is closed activating solenoid 36 which pulls ratchet 37 against wheel 38 turning it 90 degrees. This wheel is also con-

nected to valve 5 and switch 32 via mechanical linkage 28. This valve 5 and switch 32 are turned 90 degrees to the position shown in Figure 5. The electrical circuit through switch 32 is completed and solenoids or other means associated with valves 9, 10, 12 and 13 are activated turning each of these valves 90 degrees. Valve 5 is now turned to open leg 2 to the oil formation and leg 1 is full of water. The cycle is repeated in the opposite direction since ratchet wheels 35 and 27 are connected to turn mechanical linkage 28 in the opposite direction than did wheels 31 and 38. Valve 5 turns from the position as shown in Figure 5 to the position shown in Figure 6 when the oil level reaches sensing element 18 and then turns to the position as shown in Figure 3 (the original position) when the water level in leg 1 falls to sensing element 15. At the same time valve 5 is turned from the position of Figure 6 to the position of Figure 3, valves 9, 10, 12 and 13 all change positions as shown since again switch 32 now completes the electrical circuit.

As has been indicated, my invention is not limited to this particular control system. For example, these sensing elements can be capacitance means for sensing liquids. The ratchet wheels are shown as being directly connected to valve 5 and connected through a switch to valves 9, 10, 12 and 13. These valves 5, 9, 10, 12 and 13 can be electrically or otherwise driven (i. e. hydraulic, or compressed gas) and the mechanical linkage 28 driving a switch which upon changing positions causes the valve to be activated. In the last case, the ratchets can all turn in the same direction turning the switch through 4 positions. Other modifications of the control system can be made without departing from the scope of this invention.

Referring to Figure 2, reversible pump 19 is mounted in one leg of the U-tube to supply the additional force required to overcome friction and to lift the oil. This pump can be free turning when no power is applied thereto or a bypass system can be installed which will allow the oil to flow in that leg of the U-tube. It will be obvious that instead of using one reversible pump, two pumps can be used, one in each leg. Valves 20 and 21 are respectively installed in legs 1 and 2 above the level of the water. These are three-way valves which are vented via vents 22 and 23. It will be obvious that instead of using three-way valves, separate valves can be used on a vent line or if conduit 8 is open to the atmosphere, no valve would be needed in the top of the tube legs. These vents are used to prevent the pump 19 from pulling a vacuum on the leg when it moves the water from one leg to the other. The remaining portion of the apparatus is the same as was described for Figure 1 and similar reference numerals are used.

In the operation of this embodiment, valve 5 will be initially opened to leg 1 and tube 6. Valve 20 will be opened to leg 1 and to storage line 8 while valve 21 is opened to leg 1 and vent 23. When the oil rises in leg 1 to sensing element 17, valve 5 will open to the two legs and pump 19 will be started to operate in the direction of leg 1. When the water level in leg 2 passes element 16, pump 19 will stop, valve 5 will open to leg 2 and tube 6, valve 20 will open to leg 1 and vent 22, and valve 21 will open to leg 2 and storage conduit 8. The cycle will then be reversed as was the case in the embodiment of Figure 1.

I have described my invention in two of its preferred embodiments. Those skilled in the art will see many modifications and uses for my invention which can be made without departing from the scope thereof. I have shown the control mechanism mounted within the well. For ease of access, this mechanism can be mounted on the surface. Where the liquid being lifted has no pressure which would make it flow up one leg, the bottom of the U-tube can be lowered into the well beneath the liquid level. In this latter case, the seal 7 would be below

the liquid level. Another modification would involve using a vacuum on the leg of the U-tube containing the oil. Still another modification would involve using a switch mechanism on check valve 24. When the oil ceases running through this valve and the valve closes, the valve 5 would change. This latter modification would eliminate sensing elements 17 and 18 and would have the advantage of filling the U-tube leg with a maximum amount of oil for each cycle. Still another modification would be to start and stop each cycle responsive to a time cycle. This latter modification can advantageously be used where the liquid to be lifted has a substantially constant flow. In this case, sensing elements 17 and 18 would not be used and sensing elements 15 and 16 would not be required but these latter two would be useful to insure the column of water not being blown over the top of the leg where a compressed gas is used as the source of additional force. Those skilled in the art will readily recognize the fact that two concentric tubes would be equivalent to the U-tube. For example, a tube can be placed in the casing. Other arrangements of the two legs can be used without departing from the scope of this invention. However, for the most satisfactory performance, the two legs should be of substantially equal volume.

I claim:

1. An apparatus for lifting liquids comprising in combination a three way valve, two vertical tubes joined at their lower extremity to two ports of said three-way valve, a quantity of liquid in said tubes, power means operatively connected to said three-way valve for rotating said three-way valve from a first position wherein said valve opens only to one of said tubes and to the third port of said three-way valve to a second position wherein said three-way valve opens only to the two said tubes then to a third position wherein said three-way valve opens only to the second of said tubes and the said third port, and fluid propulsion means operatively connected to one of said tubes for moving said liquid from one of said tubes to the other of said tubes when said three-way valve is opened only to the two said tubes.

2. An apparatus for lifting liquids comprising in combination a three way valve, a storage conduit, a U-tube having a first and a second leg joined at the bottom of the U through two ports of said three-way valve and the top of each leg joined to said storage conduit; a tube projecting downward from the third port of said three-way valve; a volume of liquid heavier than and non-miscible with the liquid to be lifted substantially filling said first leg when said three-way valve opens to said second leg and said projecting tube; a valve in each said leg between the maximum level of said volume of heavy liquid and said storage conduit, each said valve being open to the storage conduit when its associated leg is open to the projecting tube and being closed to the storage conduit when the opposite leg is open to the projecting tube allowing liquid to be lifted to flow into said opposite leg; power means operatively connected to said three-way valve for turning the said three-way valve from a first position wherein it is open to said second leg and said projecting tube to a second position wherein it is open to the two said legs, said heavy liquid flowing from said first leg to said second leg when said three-way valve is in said second position; fluid propulsion means operatively connected to said leg containing said heavy liquid for applying a force to said heavy liquid thereby overcoming friction and lifting said liquid to be lifted to said storage conduit; combination power means operatively connected to said three-way valve for changing said three-way valve from said second position to a third position wherein said valve is open to said first leg and said projecting tube and simultaneously reversing the position of said valves at top of the U-tube and means operatively connected to said power means for reversing this cycle.

3. An apparatus for lifting liquids comprising in combination a three way valve, a U-tube having a first and

second leg joined together at the bottom of U through two ports of said three-way valve; a tube projecting down from the third port of said three-way valve into the liquid to be lifted; a power means operably connected to said three-way valve for rotating said three-way valve; a controller for said power means; a volume of a second liquid in one of said legs; a liquid sensing element in each of said legs operably connected to said controller so that said three-way valve is changed from a first position wherein said valve is open to said first leg and said projecting tube when said volume of second liquid is in said second leg to a second position wherein said three-way valve is open to both said legs, each said sensing element being responsive to the liquid being lifted; means for moving said volume of second liquid from one leg to the other leg when said valve is in said second position; a liquid sensing element in each said leg closely spaced to said three-way valve and operably connected to said controller so that said three-way valve is changed from said second position to a third position wherein said valve is open to the opposite leg and the projecting tube responsive to all of the said second liquid being transferred from one leg to the other; and means operatively connected to said power means for reversing this cycle.

25. 4. An apparatus for lifting liquids comprising in combination a three way valve, a U-tube having a first and second leg joined at the bottom of the U to two ports of said three-way valve; a tube projecting from the third port of said three-way valve into a first liquid to be lifted; a storage conduit; valved conduit means operatively connecting the top of each said leg to the storage conduit; a column of a second liquid in said second leg when said three-way valve opens to said first leg and said projecting tube; a compressed gas supply; valved means operatively connecting said compressed gas supply to the top of each said leg; combination power means operatively connected to all of said valves for opening and closing all of said valved conduit means and said three-way valve; a controller operably connected to said means for opening and closing said valves; a first liquid sensing element in said first leg operably connected to said controller to change said three-way valve from a first position wherein it is open to said first leg and to said tube projecting therefrom to a second position wherein said three-way valve is open to both legs responsive to said first liquid rising in said leg; a second liquid sensing element in said second leg closely spaced to said three-way valve operably connected to said controller to change said three-way valve from said second position to a third position wherein said second leg is open to said tube projecting therefrom, simultaneously changing all of valves in said valve means from a first position wherein the said first leg is open to storage, said second leg is closed to storage, said second leg is open to said gas supply, and said first leg is closed to said gas supply to a second position wherein all said open valves are closed and all said closed valves are open responsive to said column of second liquid in said second leg flowing to said first leg; and a third and fourth liquid sensing elements corresponding to said first and second liquid elements in the opposite legs therefrom, said third and fourth liquids sensing elements being operably connected to said controller to change said valves in the opposite direction responsive to similar changes in liquid levels in the opposite legs.

55. 5. An apparatus for lifting liquid comprising, in combination, a U-tube having a first and a second leg, a storage conduit; a first valved means operatively connecting the first leg to said storage conduit; a second valved means operatively connecting the said second leg to said storage conduit; liquid pumping means operatively connected in the bottom of said U-tube to force liquid therethrough; a three-way valve in the bottom of said U-tube, said three-way valve having separate ports connected to said first and second legs; a tube projecting from the third port of said three-way valve; power means

operatively connected to said valves for turning said three-way valve to a first position wherein said first leg opens to said tube, opening the valve in first said valved means between said first leg and said storage conduit, and closing the valve in second said valved means between said second leg and said storage conduit; a column of liquid heavier than and non-miscible with the liquid being lifted in said second leg, power means operatively connected to said three-way valve and said pumping means responsive to the level of liquid to be lifted rising in said first leg, to change said three-way valve from said first position to a second position wherein said three-way valve opens to both said legs and for starting said pumping means so as to pump said column of liquid from said second leg to said first leg thereby lifting the liquid to be lifted in said first leg; combination power means operatively connected to said pumping means and to said valves for substantially simultaneously stopping said pumping means, changing said three-way valve from said second position to a third position wherein said second leg is open to said projecting tube, changing said first valved means from open to closed position, and changing said three-way valve from said second position to a third position wherein said second leg is open to said projecting tube, and changing said second valved means from closed position to open position; and means operatively connected to said power means for reversing the cycle.

6. The apparatus of claim 5 wherein the liquid pumping means is a reversible liquid pump.

7. The apparatus of claim 6 wherein the valved means comprises a three way valve having a vent port, said three way valve being operatively installed to connect

vent and one of said legs in a first position and to connect same leg to storage in a second position.

8. An apparatus for lifting liquids comprising in combination two vertical tubes joined at the bottom to two ports of a three-way valve; conduit means operatively connected to said three-way valve for admitting a first liquid to one of said tubes when said three-way valve is open to that said tube and the third part of said three way valve; a quantity of a second liquid in said tubes; 5 a float and an associated mercury switch mounted in each said tube near the bottom thereof so that said switch is closed when said float is down due to the absence of liquid and is open when said float is lifted by liquid; an additional float and associated mercury switch 10 in each said tube intermediate said tube top and bottom and so mounted that said switch is closed when said float is lifted by liquid and is open in the absence of liquid; a solenoid operated ratchet associated with and operably connected with each said mercury switch so arranged 15 as to move the ratchet each time the associated mercury switch is closed; and a mechanical linkage connecting said three-way valve to each said ratchet so that said mechanical linkage will turn said three-way valve 90 degrees in one direction each time a mercury switch is 20 closed in the bottom of one tube or the top of the other tube and will turn the said three-way valve 90 degrees in the opposite direction each time a mercury switch similarly located in the opposite tubes is closed.
